UNITED STATES PATENT OFFICE.

JOSEPH ATWOOD WHITE, OF PHILADELPHIA, PENNSYLVANIA, ASSIGNOR TO THE MOORE AND WHITE COMPANY, OF PHILADELPHIA, PENNSYLVANIA, A CORPORATION OF PENNSYLVANIA.

LAYBOY.

1,172,088.

Specification of Letters Patent. Patented Feb. 15, 1916.

Application filed March 12, 1913. Serial No. 753,815.

To all whom it may concern:

Be it known that I, JOSEPH A. WHITE, a citizen of the United States, residing in Philadelphia, Pennsylvania, have invented 5 certain Improvements in Layboys, of which the following is a specification.

My invention relates to certain improvements in lay boys used in piling sheets of paper after they have been cut or printed.

10 The object of my invention is to construct the lay boy so that the platform carrying the paper will be suspended from an overhead framework to allow for the insertion of a truck under the platform and to allow for 15 the free access of the operator to the pile of paper during the operation of piling.

The invention also relates to the means whereby the platform can be readily detached from the means by which it is suspended so that it can be quickly removed 20 from the machine.

In this application I lay no claim to the mechanism for piling the paper.

In the accompanying drawings: Figure 1 25 is a sectional view of a lay boy illustrating my invention; Fig. 2 is a diagrammatic perspective view showing the platform in dotted lines with the truck located in position under the platform; Fig. 3 is an end view of 30 the platform and carrying bar; Fig. 4 is a detached perspective view of a detail; Fig. 5 is a view of a modification of the suspending means; and Fig. 6 is an enlarged portion of Fig. 1.

35 Referring to the drawings, 1 is the frame of the lay boy.

2 is the platform upon which the paper is to be piled.

3 is the overhead frame, projecting from 40 the main frame 1 as illustrated in Fig. 1, supported by a post 4 at each side of the machine or suspended from a beam 5, as illustrated in Fig. 5 so as to leave all of the space or a portion thereof under this overhanging 45 frame clear for the paper and to allow for the examination and sorting of the paper by the operator. The posts 4—4 may be close to the machine or they may be arranged some distance from the machine, depending upon 50 the location of the lay boy in reference to other machines or other posts in the building.

55 6—6 are two longitudinal shafts, one at each side of the machine and adapted to suitable bearings 7 secured to the overhead frame 3. On each shaft are two chain drums

8—8^a and from these chain drums are suspended chains 9 and 10 respectively. The chain 9 is attached at its lower end to a beam 11 adapted to guides 12 in the main frame 1, while the chain 10 has a ring 13 at its lower end through which passes the end of the bar 14, which is preferably grooved at 15, as shown in Fig. 3, so that the ring will fit in this groove and will prevent the bar from moving longitudinally. The platform 2 is 65 carried at its inner end by the beam 11 and at its outer end by the bar 14.

16 is a transverse shaft adapted to bearings in the frame 1 and on this shaft are two worms 17 which mesh with worm wheels 70 18 secured to each shaft 6. The shaft 16 is the driving shaft and imparts motion through this gearing to the two shafts 6 so as to lower the paper as the pile increases in height. In an application for patent filed by me on the 75 10th day of August, 1911, Serial No. 643,325, the mechanism for actuating this shaft is controlled by the paper closing the air passage leading to the pneumatic operating mechanism which automatically lowers the 80 pile of papers as the pile increases. The mechanism in the present instance is controlled by the fingers resting on the top sheet of paper of the pile so that, as the pile increases, the fingers release mechanism which 85 causes the shafts to turn and to lower the platform carrying the paper a certain distance.

19 is a transverse rock shaft having fingers 20 which rest on the top sheet of a pile of 90 paper. On the end of this rock shaft is an arm 21 counterbalanced by a weight 22 so as to make it sensitive.

23 is a lever pivoted at 24 and has an eye through which the arm 21 extends. The short arm of this lever is connected to a spring 25 so as to cause the arm to move away from the rock shaft 19. Pivoted on the large arm of the lever 23 is a pawl 26 which is arranged to engage the ratchet teeth on the wheel 27 secured to a shaft 28 and on this shaft is a sprocket wheel 29 around which passes a drive chain 30 which also passes around a sprocket wheel 31 on the shaft 16 so that any movement imparted to the shaft 28 will be transmitted to the shaft 16 and to the platform 2.

32 is a driven shaft having an eccentric 33 on which is mounted a block 34 attached to an arm 45 pivoted at 35 to the frame of 110

the machine. This block has an oscillating movement due to the eccentric.

When the pile of paper is at its normal height, then the lever 23 is outside of the path of the block 34, due to the fact that the arm 31 on the rock shaft holds it out of position, but when the pile of paper increases in height, it lifts the fingers 20, which rock the shaft 19, and releases the lever 23 and its spring 25 forces it into the path of the block 34. This block is moved laterally, which causes the pawl 26 to move and to push the ratchet wheel forward a number of teeth, causing the platform 2 to be lowered and when the top of the paper is again at the normal height, then the arm 21 again engages the lever 23 and holds it out of the path of the block 34. The paper is fed to the pile by means of two endless belts 36 and 37.

The construction of the feeding mechanism will depend upon the character of the machine to which the lay boy is attached.

In Fig. 5, I have illustrated a modification of the invention in which the platform 2 rests upon two detachable bars 14^a which are suspended by the two chains 9^a from the two shafts 6^a and when the platform 2 is lowered on to the track 38 then both bars 14^a are removed.

In the construction illustrated in Fig. 1, only one bar 14 is removed, the beam 11 being lowered to a position clear of the platform, when the platform is on the truck.

In Fig. 5, I have shown the overhead frame 3^a suspended from a beam 5 instead of being supported by the vertical posts 4. This beam may be supported in turn by posts or may form part of the overhead structure of the building in which the machine is mounted.

The jogging mechanism, Fig. 1 for keeping the sheets of paper in the proper position on the pile consists of a bar 39 located at each side of the machine, having arms 40 to which are secured the plates 41 which extend on each side of the pile of paper. The joggers are moved laterally so as to pile the paper evenly on the platform. At the end of the machine is a stop 42 and side guides 43 suspended from a frame 44 longitudinally adjustable in the overhead frame 3.

The operation is as follows: It is desir-

able to have the top of the pile of paper always at the same height so that sheet after sheet of paper can be laid upon the pile at the same point. The platform 2 rests upon the two beams or cross bars which are suspended from the overhead structure by chains or ropes and these chains pass around drums on shafts which are turned in unison by mechanism previously described, which is turned in the present instance by the fingers resting on the top of the paper so that as the paper increases in height the mechanism will be thrown into operation and will automatically lower the platform. When, as in Figs. 1, 2 and 3, the predetermined height of the pile of paper is reached, then the platform 2 is lowered on to a truck 38 which is located directly under the overhanging structure and the bar 14 is detached from the chains 9 and removed so that the truck, with the platform and the pile of paper thereon, can be readily removed from under the overhanging structure at the front or at either side and the cross bars 14 replaced and another platform placed in position.

By making the overhanging structure, as shown, not only can the truck be readily moved under the structure, but access may be had to the pile of paper from either side to remove imperfect sheets, when necessary.

I claim:

The combination in a lay-boy, of a frame; an extension at the upper end of the frame; means for supporting the extension independent of the frame and some distance from the outer end thereof; two longitudinal shafts, one on each side of the extension; a transverse shaft geared to the longitudinal shafts; means for actuating the transverse shaft; drums at each end of each longitudinal shaft; chains depending from the drums; a cross bar secured to the lower end of each inner chain; a cross bar detachably secured to the outer ends of the outer chains; and a platform carried by the cross bars.

In testimony whereof I have signed my name to this specification in the presence of two subscribing witnesses.

JOSEPH ATWOOD WHITE.
